UNITED STATES PATENT OFFICE

WILLIAM E. WOODARD, OF FOREST HILLS, NEW YORK

LOCOMOTIVE

Application filed March 12, 1930. Serial No. 435,067.

This invention relates to locomotives and more particularly to integral frame constructions, especially for large locomotives of great power.

In general my invention has to do with a construction in which the main frame, the cylinders, crosshead guides, guide brackets and valve motion brackets are all cast integral.

More specifically the invention has to do with a novel disposition of the parts whereby a greatly improved construction of unitary locomotive frame structure is secured.

Another object of the invention is to provide a construction such that the cylinder structure and the cylinder saddle structure may be of great strength and rigidity and afford stiffness for the guide and valve motion supports.

How the foregoing, together with such other objects and advantages as may herein-after appear, or are incident to my invention, are realized is illustrated in the accompanying drawings, wherein—

Fig. 1 is a more or less diagrammatic side elevation of a locomotive provided with my improved integral frame structure.

Fig. 2 is a plan view of the frame structure.

Fig. 3 is a front elevation of Fig. 1 partly in section.

Fig. 4 is a section taken substantially on the line 4—4 of Fig. 2.

Referring now to Fig. 1, the reference numeral 7 indicates the boiler and superstructure carried in the usual manner on the main frame indicated as a whole by the reference character A and by the frame B articulated with the main frame and transmitting pull. The drivers, of which there are more than two, are indicated at 8.

The main frame comprises the usual side members 9 suitably connected at intervals by cross members 10 and provided with pedestal jaws 11 for the driving boxes not shown. The forward end of the main frame takes the form of a horizontally disposed plate 12 provided with upstanding and depending ribs 13 and 14 extending longitudinally thereof in substantial alignment with the side members 9. Transverse ribs 15 and 16 respectively,

rise from and depend below the plate 12 and connect the pairs of ribs 13 and 14 and provide a saddle structure. Similar transverse ribs 17 connect the pairs of ribs 13 and 14 to the rear of the saddle.

The plate 12 is widened, i. e., it projects laterally beyond the pairs of ribs 13 and 14 and has cast integral therewith the cylinders 18 and the brackets 19 for the main crosshead guides 20. The brackets 19 have cast integral therewith the valve motion brackets 21.

The widened construction of the plate 12 makes it possible to carry pairs of ribs 22 and 23 laterally outward from the ribs 13 to the main cylinders 18 and valve cylinders 18a and also makes it possible to carry similar pairs of ribs 24 and 24a, above and below the plate, to the main crosshead guide brackets and the valve motion brackets. These portions 14a of the ribs 14, from the region of the forward ribs 15 and 16 to the side frame members 9 proper, are thickened for strength. The ribs 13 rise upwardly from each end toward the cylinder saddle (see Figs. 1 and 3) and merge with the pad portion of the saddle.

Thus it will be seen that a very strong, rigid and stiff front end construction is secured by virtue of which all parts are kept in alignment under service conditions, even though normal maximum distance between cylinders is maintained.

I claim:—

1. An integral locomotive frame structure comprising a main frame widened out between the cylinders and the forward drivers to extend laterally beyond the planes of the drivers, and cylinders and crosshead guide brackets formed integrally with such widened portion.

2. An integral locomotive frame structure comprising a main frame widened out between the cylinders and the forward drivers to extend laterally beyond the planes of the drivers, and cylinders and crosshead guide brackets formed integrally with such widened portion, the widened portion being provided with reinforcing ribs joining with the cylinder walls and the brackets.

3. An integral locomotive frame structure comprising a main frame widened out at its

forward end to extend laterally beyond the planes of the side members of such frame, and cylinders and crosshead guide brackets formed integrally with such widened portion, 5 the widened portion being provided with upper and lower reinforcing ribs joining with the cylinder walls and the brackets.

4. An integral locomotive frame structure comprising a main frame terminating at its 10 forward end in a horizontal plate-like portion of greater width than the frame proper, cylinders and crosshead guide brackets marginal of the said portion, and pairs of upper and lower transverse ribs joining with the 15 cylinders and brackets.

5. An integral locomotive frame structure comprising a main frame terminating at its forward end in a horizontal plate-like portion of greater width than the frame proper, cylinders and crosshead guide brackets marginal of the said portion, and pairs of upper and lower transverse ribs joining with the cylinders and brackets, together with longitudinal upper and lower ribs in approximate alignment 20 with the side members of the frame and intersecting the first mentioned ribs.

6. A integral locomotive frame structure comprising a main frame terminating at its forward end in a horizontal plate-like portion 25 of greater width than the frame proper, cylinders and crosshead guide and valve motion brackets marginal of the said portion, and pairs of upper and lower transverse ribs joining with the cylinders and brackets.

7. An integral locomotive frame structure comprising a main frame terminating at its 30 forward end in a horizontal plate-like portion of greater width than the frame proper and intersecting ribs on the plate-like portion providing a reinforced saddle portion.

8. An integral locomotive frame structure comprising a main frame terminating at its forward end in a horizontal plate-like portion of greater width than the frame proper and 45 intersecting ribs on the plate-like portion providing a reinforced saddle portion having cylinders integral therewith.

9. An integral locomotive frame structure comprising a main frame terminating at its 50 forward end in a horizontal plate-like portion of greater width than the frame proper and longitudinal and transverse upper and lower intersecting ribs integral therewith, the transverse ribs starting at points laterally outside the planes of the side members 55 of the frame.

10. An integral locomotive frame having those portions which are provided with pedestals located within the planes occupied 60 by the driving wheels and having that portion which extends forward of the driving wheels between said wheels and the cylinders widened laterally beyond such planes to carry the cylinders and carried upwardly to 65 provide a saddle.

11. An integral locomotive frame having those portions which are provided with pedestals located within the planes occupied by the driving wheels and having that portion which extends forward of the driving wheels 70 between said wheels and the cylinders widened laterally beyond such planes to carry the cylinders and carried upwardly to provide a saddle, and cylinders cast integral with such widened portion. 75

12. An integral locomotive frame having those portions which are provided with pedestals located within the planes occupied by the driving wheels and having that portion which extends forward of the driving 80 wheels between said wheels and the cylinders widened laterally beyond such planes to carry the cylinders and carried upwardly to provide a saddle, said widened portion having cast integral therewith the cylinders 85 and the cross-head guide supports.

13. An integral locomotive frame having those portions which are provided with pedestals located within the planes occupied by the driving wheels and having that portion which extends forward of the driving 90 wheels between said wheels and the cylinders widened laterally beyond such planes to carry the cylinders and carried upwardly to provide a saddle, said widened portion having cast integral therewith the cylinders and the cross-head guide supports and the valve motion supports. 95

In testimony whereof I have hereunto signed my name.

WILLIAM E. WOODARD.
